MICROPHONE

Barton A. Proctor, Larchmont, N. Y., assignor to
 B. A. Proctor Company, Inc., New York, N. Y.,
 a corporation of New York

Application December 5, 1939, Serial No. 307,560

5 Claims. (Cl. 179—115.5)

This invention relates to microphones for converting sound energy into electrical energy. The invention has utility in connection with public address systems, radio, telephony, sound recording, and, in fact, any purpose for which a microphone can be used.

It is an object of the invention to provide a microphone which is highly sensitive and which responds with a high degree of fidelity to variations of sound frequency and intensity.

It is a further object of the invention to provide a microphone employing a vibratory diaphragm having electrical and magnetic parts associated with it, and to enclose and seal the electrical and magnetic parts against ingress of dirt and moisture in such manner that no substantial back pressure will be developed against the diaphragm at any time.

A further object of the invention is to provide a microphone structure which is simple and economical to manufacture and which is sturdy and dependable in use.

Other objects and advantages will hereinafter appear.

The single figure of the drawing discloses in section a microphone embodying the invention.

The illustrated microphone comprises a cup-like shell member 1 of magnetic material such as hard steel. A bolt 2 is passed through the back of the member 1 and through a block 3 of magnetic material, and is threaded into a block 4 of magnetic material for clamping the shell and the blocks firmly to one another. The block 4 terminates in a round boss 5 which has a circular bore 6 formed centrally thereof. This hub 5 constitutes one pole piece of a composite structure of which the block 3 and the shell 1 also form elements. A plate or disc 7 of magnetic material is fixed in the mouth of the shell 1, being fitted into an internal rabbet 8 formed in the shell. The plate 7 is formed with a central opening 9 which is concentric with the boss 5 and which extends around the boss 5 at a short distance from it.

A flexible diaphragm 10 of resilient, non-magnetic material is disposed across the mouth of the shell 1 and secured against the forward face of the shell. The diaphragm is made rigid at its outer margin by the spinning around such margin of a ring 11 of non-magnetic metal. The diaphragm includes an annular area which is corrugated, the alternate ridges and valleys extending circularly and concentrically around the center of the diaphragm. The central portion of the diaphragm is pressed outward or forward to form a substantially rigid boss 12.

A perforated shield plate 13 of non-magnetic material is formed with a flange 14 which bears against the ring 11 for clamping the diaphragm in place. A retaining ring 15 is threaded onto the shell 1 and is formed to overlie the shield plate 13, being effective to hold the shell, the diaphragm 10, and the shield plate 13 in assembled relation and clamped firmly to one another. The retaining ring 15 extends only a short distance inward over the shield plate 13, being formed with a large central opening 16 which leaves the shield plate 13 almost fully exposed to the speaker.

The diaphragm 10 has cemented to it a small coil 17 composed of a multiplicity of turns of fine wire. The coil 17 is oscillated longitudinally in the space between the boss 5 and the plate 7. The plate 7 forms one pole piece of the composite magnet made up of the plate 7, the shell 1, and the blocks 3 and 4, and the boss 5 forms the other pole piece of the magnet. The coil, therefore, is arranged to move in the region of maximum flux intensity.

Movement of the coil toward the right will induce current to flow in one direction through the coil, and movement of the coil toward the left will induce current to flow in the other direction through the coil. The current impulses thus generated will respond in frequency to the frequency of the diaphragm vibrations, and will respond in intensity to the intensity of the diaphragm vibrations.

Lead wires 18 and 19 are connected to opposite ends of the coil wire. These lead wires are cemented to the rear face of the diaphragm 10 and extend through a passage 20 formed in the shell 1. The wires 18 and 19 may be connected in the conventional manner for utilization of the voice current which has been induced in the coil 17.

It is not desirable that air shall be trapped behind the diaphragm 10 in such a way as to create back pressure against the diaphragm. For this reason the plate 7 is formed with a number of holes 21 and the shell 1 is formed with a number of holes 22.

In order, however, that the current inducing parts may be protected from dirt, moisture and other deteriorating atmospheric constituents, means are provided for sealing such parts. A plate 23, which may be of any suitable material, is affixed within the shell 1 against an internal shoulder 24 to form a sealed joint with the shell. The plate 23 is formed with a central opening 25 which fits the block 3 and forms a sealed joint

therewith, and with a series of openings 26. A diaphragm 27 which is impervious to dirt and atmospheric moisture and is formed of highly flexible material, such as sheet rubber, is cemented to the solid margins of the plate 23 adjacent the shell 1 and the block 3 and has its slack intermediate portion bowed or bellied to the rear as illustrated. The diaphragm 27 forms an absolute seal against ingress of atmospheric moisture and dirt, but is freely capable of distortion so that no substantial back pressure of air against the diaphragm 10 can develop at any time.

I have described what I believe to be the best embodiments of my invention. I do not wish, however, to be confined to the embodiments shown, but what I desire to cover by Letters Patent is set forth in the appended claims.

I claim:

1. A microphone comprising, in combination, a flexible vibratory diaphragm, means secured to the central portion of the diaphragm and responsive thereto for inducing electrical currents, and means including the diaphragm for housing the current-inducing means and for protecting the current-inducing means against exposure to constituents of the atmosphere, said housing and protective means including a slack, sealing member of freely, flexible sheet material which is impervious to dirt and moisture, and a supporting means arranged to support the sealing member at the rear of the diaphragm and in alignment therewith and spaced therefrom by a substantial distance.

2. In an acoustic device, in combination, a cup-like shell, a center post extending axially within the shell from the base of the shell, a plate affixed in the mouth of the shell, said plate having a central opening through which the center post extends concentrically to define a thin, annular space of uniform thickness, all of said parts being composed of permeable material for forming a composite magnetic structure, the plate having holes formed in it between the central opening and the outer boundary, and said shell having holes formed in it in a region remote from the plate, a partition plate secured across the shell and around the center post between the first mentioned plate and the holes in the shell, said partition plate lying wholly within the shell and formed with a series of holes in an annular portion thereof, and a freely flexible, diaphragm impervious to dirt and moisture and composed of non-metallic material secured to

the inner and outer margins of the partition plate in position to completely cover the holes therein.

3. A microphone comprising, in combination, 5 a cup-like shell, and a flexible, vibratory diaphragm secured across the front of the shell and forming therewith a chamber which is completely closed save that the shell is open to the atmosphere at the rear end thereof, means in the 10 chamber associated with the diaphragm and cooperative therewith for inducing electrical currents, and sealing means disposed wholly within said shell for completely preventing access of atmospheric constituents to the forward portion of the chamber, said sealing means including a slack sealing member of freely flexible material impervious to dirt and moisture.

4. An acoustic device, comprising, in combination, a cup-like shell, a center post extending axially within the shell from the base of the shell toward the front thereof, a plate affixed in the front end of the shell, said plate having a central opening through which the center post extends concentrically to define a thin, annular 20 space of uniform thickness, all of said parts being composed of magnetic material for forming a composite magnetic structure, the plate having holes formed in it between the central opening and the outer boundary, and said shell being opened to the atmosphere at the rear end thereof, a flexible vibratory diaphragm covering the mouth of the shell and cooperating with the shell to form a chamber, and a freely flexible 25 diaphragm formed of non-metallic material impervious to dirt and moisture disposed within and transversely of the shell far behind said plate and sealing the forward portion of said chamber against communication with the atmosphere.

5. An acoustic device comprising, in combination, a cup-like shell formed of magnetic material and provided with an inwardly extending annular pole piece and a second pole piece having an end disposed concentrically within said 40 annular pole piece, a vibratory diaphragm mounted on and extending across the front portion of the shell and having a voice coil disposed between said pole pieces, and means comprising a freely flexible rubber diaphragm disposed transversely between the second pole piece and the shell and arranged to prevent air in the rear portion of the shell from passing forwardly and coming in contact with the voice coil.

BARTON A. PROCTOR.
